COMBINED SAVINGS BOX AND RADIO RECEIVER OR SIMILAR ARTICLE

Heihachiro Wada and Susumu Nakayama, Tokyo, Japan, assignors to Crown Radio Corporation, Taito-ku,
Tokyo, Japan, a corporation of Japan

Filed Oct. 29, 1965, Ser. No. 87,954

Term of patent 14 years

(Cl. D56—4)

FIG. 1

FIG. 2

FIG. 3

FIG. 4

FIG. 5

FIG. 6

FIG. 7

FIG. 1 is a front elevational view of a combined savings box and radio receiver or similar article, showing our new design;

FIG. 2 is a back elevational view;

FIG. 3 is a right side elevational view, the left side being substantially a mirror image thereof;

FIG. 4 is a top plan view;

FIG. 5 is a bottom plan view;

FIG. 6 is a top plan view thereof, with its cover removed; and

FIG. 7 is a perspective view thereof with its cover opened.

We claim:

The ornamental design for a combined savings box and radio receiver or similar article, substantially as shown and described.
